GREASE DISCHARGE DEVICE

Cleo Harris, Cincinnati, Ohio, assignor to The Cincinnati Ball Crank Company, Cincinnati, Ohio, a corporation of Ohio

Application November 29, 1932, Serial No. 644,844

3 Claims. (Cl. 221—47.3)

This invention relates to lubricating apparatus and is particularly directed to improvements in small portable hand operated grease supply pumps or guns for servicing lubricating fittings and the like.

It has been found necessary to make these hand guns in a variety of types for a range of volume or pressure. The ejecting piston at the forward end of the guns is disposed for action on the 10 volume of grease urged to the forward end of the gun by some booster means and is operated by means of a hand lever. The discharge piston is varied in diameter depending on the pressure or the volume of feed desired.

16 It is the object of this invention to provide an improved hand operated grease pump or gun of the above nature in which different size pistons are readily incorporated without necessitating an entirely reconstructed gun for each size. More 20 specifically, the purpose is to provide that a different size piston may be readily introduced in a standard gun merely by removing the piston and cylinder and replacing the same with a piston and cylinder of the desired diameter.

25 It is a further object of this invention to provide an improved hand gun in which the follower plate mechanism and mounting are improved for a uniform grease feeding action and for positively holding the piston in fully retracted 30 position in the barrel during the time that the piston is being reloaded so as to take the feeding pressure off the grease at this time.

It is a still further object of this invention to 35 provide a co-related piston and discharge control valve for the grease gun in which the final action of the piston in its discharge strokes is to unseat the valve by direct contact so as to prevent the formation of air pockets in the cylinder and to insure a complete discharge of grease and any 40 air from the cylinder at each stroke. An arrangement of the cylinder is also provided whereby the feeding or loading of grease into the discharge cylinder takes place easily and positively for a regular discharge of grease from the cylinder 45 upon each stroke of the piston.

Other objects and further advantages will be more fully apparent from a description of the accompanying drawings, in which:

Figure 1 is a longitudinal sectional view of the 50 improved hand gun showing the details thereof and illustrating a low pressure development size, and showing the end of the discharge hose in section for illustrating the details of the swivelling coupling means.

55 Figure 2 is a fragmentary view of the forward

end of the gun illustrating the head thereof with replaced cylinder and piston for high pressure discharge.

Figure 3 is a sectional view taken on line 3—3, Figure 1, illustrating the latch for holding the 60 follower piston in retracted position.

Figure 4 is a fragmentary and sectional view taken on line 4—4, Figure 1, detailing the hand operated leverage for operating the gun.

Figure 5 is a fragmentary and sectional view 65 taken on line 5—5, Figure 1, detailing the follower piston and its mounting.

Figure 6 is a front view of the gun.

Figure 7 is a sectional view taken on line 7—7, Figure 1, detailing the connection of the leverage 70 to the piston.

Figure 8 is an enlarged fragmentary view of the lower end of the piston and the valve showing the piston at the limit of downstroke.

The grease gun to which the improvements are 75 applied in the present instance includes an arrangement of the operating lever and barrel, the operation of which lever relative to the barrel resembles a scissors action, these guns, therefore, being referred to as the scissors type.

Referring to the drawings, the barrel 10, in which the supply of grease is contained, is screwed into a head 11 in which the operating piston 12 and cylinder 13 are mounted at right angles to the axis of the barrel. The lever 14 which operates the piston 12 is pivoted at the forward end of the head of the gun and has its leverage end extending substantially parallel with the barrel. In the operation of the gun for the delivery of the grease, the handle or lever, operating the piston, and the barrel are moved toward and from each other after the manner of the operation of a pair of scissors.

An outlet passageway 15 extends from the lower 95 end of the cylinder, the discharge of grease from the cylinder being controlled by means of an outlet valve 16. A follower piston 17 is mounted in the barrel or cylinder containing the supply of grease and is urged against the body of grease by means of a spring 18 under compression between 100 the follower piston and the outer cylinder cap or head 19. The follower piston moves axially on a withdrawal rod 20. This rod 20 includes a nut 21 providing a shoulder or abutment at the extreme inner end of the rod and has a handle 22 fixed on its outer end beyond the cap or closure means 19.

The rod 20 is provided for the purpose of reTRACTING the follower piston and drawing grease into the barrel, which act places the spring 18 110

- under compression. When the gun barrel has been emptied and the follower piston has moved against the limit shoulder or stop 21 under the action of the spring the operator of the gun unscrews the barrel 10 from the head 11 and plunges the open end of the barrel into the grease supply. He then retracts the follower plate by grasping the handle 22 and pulling the rod through the cap 19.
- 10 When the follower plate has been fully moved back it is set in position so that the handle may be released and the gun re-assembled. The means for securing the piston in retracted position is in the form of a latch bar 23 operating in a cross slot 24 in the cap 19 and cooperating with an annular groove 25 in the hub 26 of the follower piston. The end of the hub 26 moves into a counterbore 27 of the cap 19 to bring the annular groove 25 into cooperative relation for registry with the latch bar. The latch bar is inclusive of an opening 28 traversed by the rod 20 and the latch bar is normally urged laterally against the rod by a spring 29 mounted in the inner and closed end of the cross slot. The hub of the follower plate has a tapered end 30 which imparts a cam action for moving the latch laterally so that it will slip up to and into the groove 25.
- 15 The follower plate or piston is fabricated of reversely facing gaskets 31, a washer 32 at each side of the abutted gaskets, the main hub element 26 and a packing gland 33, the latter two elements being screwed together and having flanges 34 clamping upon the opposite sides of the assembled gaskets and washers. A tapered packing 35 is urged upon the rod 20 by a tapered element 36 moved against the packing by means of a spring 37.
- 20 The head 11 has a chamber 38 beyond the open end of the barrel and the cylinder 13 is disposed across this chamber. The cylinder element is inserted in a cross bore of the head from the bottom of the gun and includes a head or flange 39 secured against a packing ring on a counterbore shoulder 40 of the bore by means of a valve 45 carrier and cylinder retaining plug 41 screwed into the counterbore.
- 25 A ball valve 42 is mounted within the plug and is urged by means of a spring 43 against a seat 44 at the lower end of the cylinder for closing the end of the cylinder. The sides of the plug are slotted as at 45 adjacent the ball valve and a circular clearance groove 46 is formed by a counterturned groove in the outer surface of the plug to which groove the slots connect. The discharge passageway extends laterally from this groove and a connector plug 47 at the end of a hose 48 is screwed into this passageway. The discharge passage and hose extend angularly from the forward end of the head.
- 30 The piston 12 is inserted in the cylinder from above and is operated from above. The walls of the cylinder are slotted as at 49 so that the grease may enter from the chamber of the head, these slots being disposed substantially below the piston when in its upper limit position. A packing gland 50 is screwed into the cross bore from above for sealing about the piston.
- 35 The piston operating lever 14 has a double pivotal connection at the forward head end of the gun. Spaced links 51 are pivoted on a lug 52 of the head and are pivotally connected by a pivotal connection 53 to the end of the lever. A lug or rib 54 along and on the underside of the lever traverses a slot 55 in the upper end of the piston and is connected thereto by means of a

cross pin 56. The handle 57 of the lever is extended well along the gun barrel.

The discharge hose 48 is of rubber having terminal ends of metal. The inner terminal or connector plug 47 carries an adapter 47^a which is 80 screwed onto a nipple 47^b fixed into the head at the discharge end of the cylinder. A spring urged packing 47^c is urged against the joint between the adapter and nipple for sealing the joint since the hose is normally uncoupled at this connection or joint. The outer terminal 58 has a swivelling coupling 59 mounted thereon. The terminals and hose are connected together by pressure insertion of the hose ends in circular recesses or grooves 60 in the terminals. 90

95 The coupling is rotatably mounted on a hollow and headed stud 61 screwed into the terminal 58. A manipulating element 62 including a thumb or wing extension 63 is loosely abutted against the end of the terminal 58 and under the head of the stud 61. An intermediate element 64 is screwed into the manipulating element and snugly rotatable against the head of the stud. A cup packing 65 in a counterbore of the intermediate element is urged by a comparison spring 66 against 100 the head for sealing the passageway for the grease from the stud into the intermediate element.

105 A main coupling element piece 67 is screwed into the outer end of the intermediate element and includes bayonet slots 68 in its ends for co-operation with the fitting (not shown). This element includes cup packing elements 69 urged by a spring 70 in opposite directions, one for sealing the connection between the intermediate element and the coupling element and the other lying against a shoulder 71 and adapted to abut the end of the fitting.

110 It has also been arranged that the same ball valve 16 may be used for all of the interchangeable cylinders, the seats at the lower ends of the 115 bores of these different sized cylinders being formed on the same radius so as to properly seat a common ball valve.

115 In operating the gun after the barrel has been loaded and replaced and the latch 23 tripped permitting the booster piston to be moved against the grease under the influence of the spring, the barrel is grasped in one hand and the lever in the other, and the gun thereupon operated after the manner of a pair of shears or scissors. As the lever 125 and barrel are moved apart, the piston is drawn up in the cylinder, the valve 16 being closed at this time.

120 When the lower end of the piston sufficiently clears the slots in the cylinder wall, the grease 130 is moved into the cylinder under the action of the follower piston and the cylinder is thereby re-loaded for down stroke. As the lever and barrel are moved together, the piston acting on the grease in the cylinder below the slots opens the valve 135 and forces the grease out through the discharge hose and into the fitting to which the hose is coupled. At the lower limit of piston stroke the piston engages the ball and unseats it by direct contact thus assuring the escapement and discharge of any air which may have pocketed in the cylinder. 140

145 The operating lever is limited in its discharge movement, to a position just sufficient for moving the ball off its seat, by engagement of the rim or lug of the lever with the top of the packing gland screwed above the cylinder. When the operator finds it necessary to change the volume or pressure development of the gun he unscrews the valve carrier and retainer element and re- 150

moves the cylinder from its bore at the underside of the gun. The piston is readily disconnected from the lever by pulling it upwardly clear of the head and extracting the pivot pin which connects it to the lever. A different diameter cylinder and piston may then be readily inserted to suit the requirements at the particular time.

Having described my invention, I claim:

1. A grease supply gun, comprising, a head including a chamber, a headed cylinder mounted in a bore of the head and across the chamber and having its head engaged on the shoulder of a counterbore in the head, said cylinder including a passageway communicating with the chamber, a longitudinally slotted valve carrier and cylinder retainer element screwed against the head of said cylinder, a ball valve mounted in said element, a spring urging the ball valve against the lower end of said cylinder, a discharge conduit extending from the counterbore, a piston inserted in said cylinder from above, a packing gland screwed into the bore and about the upper extended end of the piston, a hand lever pivoted at the forward end of the head and pivotally connected to the upper end of the piston, a supply barrel connected to said head, and a follower piston forcing the grease into the chamber of the head, said hand lever disposed above and along the barrel.

2. A grease supply gun, comprising, a head including a chamber, a headed cylinder mounted in

a bore of the head and across the chamber and having its head engaged on the shoulder of a counterbore in the head, said cylinder including a passageway communicating with the chamber, a valve carrier and cylinder retainer element 80 screwed against the head of said cylinder, a valve mounted in said element, a spring urging the valve against the lower end of said cylinder, a discharge conduit extending from the counterbore, a piston inserted in said cylinder from above, 85 packing about the upper extended end of the piston, and a lever for operating said piston.

3. A grease discharge device, comprising, a head including a chamber, a barrel adapted to contain grease and connecting with said chamber, means 90 in the barrel for forcing the grease into the chamber, a cylinder element mounted in the head transverse to the axis of the barrel and disposed through the chamber of the head, said cylinder including openings in its wall connecting the interior of the cylinder with the chamber, a valve carrier and cylinder retainer element 95 screwed into the head for maintaining the cylinder in place and disposing the valve against the lower end thereof, a piston in said cylinder, a lever for reciprocating the piston, said lever connected to the piston at the upper end thereof, and a discharge conduit extending from the lower end of the cylinder.
